UNITED STATES PATENT OFFICE

119,906

DESIGN FOR A HANDBAG OR SIMILAR ARTICLE

Martin L. Nattenheimer, Chicago, Ill.

Application March 4, 1940, Serial No. 90,657

Term of patent 3½ years

To all whom it may concern:

Be it known that I, Martin L. Nattenheimer, a citizen of the United States of America, residing at Chicago, in the county of Cook and State of Illinois, have invented a new, original, and ornamental Design for a Handbag or Similar Article, of which the following is a specification, reference being had to the accompanying drawing, forming part thereof.

The figure is a perspective view of a handbag or similar article, showing my new design.

The other side of the article is substantially like the side of the handbag shown.

I claim:

The ornamental design for a handbag or similar article, as shown and described.

MARTIN L. NATTENHEIMER.
